UNITED STATES PATENT OFFICE.

SAMUEL J. SHIMER, OF MILTON, PENNSYLVANIA.

CUTTER-HEAD.

SPECIFICATION forming part of Letters Patent No. 476,563, dated June 7, 1892.

Application filed October 3, 1891. Serial No. 407,638. (No model.)

To all whom it may concern:

Be it known that I, SAMUEL J. SHIMER, a citizen of the United States of America, residing at Milton, in the county of Northumberland and State of Pennsylvania, have invented new and useful Improvements in Cutter-Heads, of which the following is a specification.

My invention has relation to improvements in cutter-heads usually called "matcher-heads" and of that class mounted on a vertical spindle and carrying upper and lower cutter-bits adapted for tonguing or grooving boards.

15 The present invention has for its primary object to adapt a circular-bit matcher cutter-head of the expansion variety or class to receive circular bits. In Letters Patent No. 293,529, of February 12, 1884, there is shown a vertically-expansible cutter-head carrying straight bits; but I have found it impossible to adapt and utilize this principle and means of expansion to a cutter-head carrying the preferred circular bits until the present invention was conceived and perfected and not until I conceived the particular form of the bit having an integral clamping-bolt, the advantages of which construction will be fully set forth hereinafter.

30 I have fully and clearly illustrated my invention in the accompanying drawings, where-in—

Figure 1 is a side view showing the cutter-head equipped with circular bits for cutting the tongues on boards. Fig. 2 is a central vertical section through the several parts or elements. Fig. 3 is a perspective of the upper section or bed-piece of the cutter-head on which the bit-seats for the bits cutting the 35 upper carve of the tongue are formed and the intermediate openings for the bits on the other sections. Fig. 4 is a perspective of the lower section of the cutter-head, showing the radial flanges for bit-seats for the lower cutting-bits and the intermediate openings for the other bits. Fig. 5 is a view of my improved circular bit, the nut being removed from the bolt projecting from the center; and Fig. 6 is a view of the expanding spring.

50 A designates the part constituting the lower section that carries the bits for cutting the upper carve on the board. This consists

of a hub or stem 1 to receive the spindle, having projecting radial flanges *b c d* extending from the base, on the upper face of which are 55 formed bit-seats 2, between which the metal is cut out, preferably in circular shape, as seen at 3, constituting openings, into which the oppositely-arranged bits of the other section project, as shown in the drawings. In 60 the bit-seats are bolt-holes *a* to take the stems of the bits. About the base of the hub 1 is formed an annular groove 4, forming a seat for the expansion-spring. The hub is screw-threaded, as seen at 5, to take the threaded 65 adjusting nut or ring and the top cap-nut, hereinafter described. In the corner of each of the flanges is a guide-pin 6, and in the opposite corner of each flange is a pin-hole 7, the former entering a pin-hole 8 in the upper 70 section of the head and the latter receiving a guide-pin 9 in that element. These pins not only serve to guide the sections in their relative positions, but also serve to maintain that relation when any adjustment is being made 75 and also keep the parts from moving upon each other in either direction. In the hub is a slot 10, which takes the end of a threaded bolt 11, projected through the shell of the other section. The vertical adjustment of 80 the parts is limited by this bolt and slot, so that the parts cannot be operatively separated beyond the limits of the slot. About the hub 1 is arranged the expansion-spring 12, seated in the annular groove 4 at the base and having its upper part seated and bearing in an annular groove 13 in the opposite section, substantially as shown.

B designates the upper section of the cutter-head. This consists of a substantial conical-shaped sleeve 14, having a bore to fit and take the hub of the other section and having the metal at the base formed with radially-projected flanges *e f g*, on the under face of which are formed bit-seats 15, in which are 90 bolt-holes 16 to take the stems of the bits. The bolt-holes in the bit-seats of each section are formed tapering for a portion of their length, as shown, so that the bits may be more firmly clamped to the head on the seat, 95 and thus prevented from turning on their seats. Between the flanges of the part B the metal is cut away, as seen at 17, forming circular openings, into which project the bits of 100

the other section, as shown in the drawings. As heretofore mentioned, in the corners of the flanges of this section are placed pins 9, and in the opposite corners are pins-holes, 5 which engage and take pins and holes of the lower section, and the threaded bolt 11 is projected through the shell of the sleeve of this section to take in the slot 10 of the hub of the lower section, and the annular groove 13 takes 10 the upper end of the expansion-spring. The top end face of the sleeve 14 is formed with V-shaped or circular projections 18 to engage with corresponding formations on the lower face of the adjusting-ring C. This adjusting- 15 ring is interiorly threaded to engage the threads of the hub 1, so that by turning the ring the section B may be vertically adjusted in either direction and the ring held in place by the intersection of these indented faces. 20 These means for adjustment are substantially identical with the means set out in Letters Patent heretofore cited and of course do not enter in the present invention, except as they may form parts of legitimate combinations 25 with my improvements. On the hub 1 is fitted a threaded clamping-cap 19, having a threaded hole 20 in its top, which takes a threaded bolt 21, the end of which bears on the end of the spindle, (not shown,) by means 30 of which the whole head may be adjusted to the proper vertical position on the spindle. The cap 19 is held against displacement by means of small set-screws 22, let through it and into hub 1, bearing with their inner ends 35 against the spindle, as indicated in Fig. 2 of the drawings.

D designates my improved circular cutting-bit. The bit portion of this may be of any of the usual approved forms of circular bits 40 with the usual notch made for tonguing or grooving boards. This circular bit is formed with a solid bottom 23, from the under face of which projects the clamping-bolt 24, formed integral with the bit. The lower portion of 45 the clamping-bolt is provided with screw-threads to take a nut 25, as seen in Fig. 5 of the drawings. The neck or upper part of this bolt is tapering, as at 26, to fit in the tapering hole of the bit-seat and make a tight, secure, 50 and strong union of the parts. These bits, having the bolts integral therewith, can be made much smaller than bits having center holes in them, and it is due to the improved construction, enabling me to make the bit of 55 small dimensions, that I adapt the expansion principle to a head having circular bits in their equipment. A circular bit made with a bolt-hole and small enough to apply to use on an expansible head, as represented in the 60 drawings, the bit being shown full size, would be so frail at the notched side that it would crack during the process of tempering and be rendered useless, since experience proves that bits of larger size with bolt-holes often break 65 while tempering. Hence this bit with integral bolt is an improvement in construction which

enables an expansion matcher-head with circular bits to be efficiently and operatively equipped with these preferred bits. By the construction and arrangement of the sections 70 of the head, so that the lower-cut bits are carried on the bottom face of the upper section of the head and the upper-cut bits on the upper face of the lower section thereof, the flanges can be made much thinner, saving 75 metal, and at the same time made narrower, with bit-seats of smaller diameter. The projecting walls of the bits, extending into the spaces of the flanges, also receive support by the walls of the spaces. 80

By reference to the drawings it will be observed that the expansibility is limited, and purposely and definitely so, to prevent an overlap of the bits in the wrong direction, since the upper-cut bits are on the lower section of the head and the lower-cut bits on the upper section thereof. Hence when the adjusting nut or ring is turned down the flanges, rims, or bit-seats are closer together and the tongue or groove made wider; but on turning 90 the nut upward the spring forces the upper section upward, causing the clearance between the bits to be narrower, and consequently forming a narrower or thinner groove or tongue.

The assemblage of the parts may readily be 95 perceived from the description and in connection with the drawings; but the arrangement of the parts may be here rehearsed. The expansion-spring is arranged on the hub of the lower section, the top section then put 100 on the hub, the adjusting ring or nut screwed down, and then the cap screwed down in place and secured by the small set-screws at its base. The bolt in the upper section is then 105 screwed in to enter the slot in the hub, and then the bits may be set, adjusted, and fixed in place.

Having thus described my invention, what I claim is—

1. A circular bit for a cutter-head, consisting of a bit and a threaded clamping-bolt integral with each other, the clamping-bolt being formed with a tapering portion between the threaded ends and the bottom of the bit, substantially as described. 115

2. In a cutter-head, the combination of a lower section consisting of a central threaded hub formed at its base with radially-projecting flanges having bit-seats on their upper faces and circular openings between the flanges, into which the bits of the upper section project, an adjustable upper section consisting of a sleeve to fit the hub of the lower section and formed at its base with radially-projecting flanges having bit-seats on their under faces and circular openings between the flanges, into which the bits of the lower section project, and means for adjusting and holding the upper section, substantially as described. 120 125

3. In a two-part cutter-head, the combination of a lower section adapted to carry the

bits to make the upper curve of the cut and an upper adjustable section adapted to carry the bits to make the lower curve of the cut, bits on the lower section, and bits on the upper section intermediate of the others, substantially as described.

4. In a cutter-head, the combination of a hub having radial flanges at its base, circular bits on the flanges, and circular spaces between the flanges, an upper adjustable section fitted on the hub of the lower section and formed with radial flanges, and circular spaces between the flanges to take in the bits on the lower section, and bits on the under face of the flange of the upper section, arranged to project in the spaces between the flanges of the lower section, substantially as described.

5. The combination, with a matcher cutter-head having radial flanges formed with bit-seats having central tapering bolt-holes, of a 20 circular cutting-bit having a clamping-bolt integral with the bit, said clamping-bolt being formed tapering adjacent to the bottom of the bit to fit the tapering bolt-holes in the flanges on the head, and a nut to clamp the bolt, sub- 25 substantially as described.

In witness whereof I have hereto set my hand in the presence of two attesting witnesses.

SAMUEL J. SHIMER.
